UNITED STATES PATENT OFFICE.

NAHO TANAKA, OF NEW YORK, N. Y.

TELEPHONE-TRANSMITTER.

1,190,813.

Specification of Letters Patent. Patented July 11, 1916.

Application filed March 27, 1915. Serial No. 17,564.

To all whom it may concern:

Be it known that I, NAHO TANAKA, a subject of the Emperor of Japan, residing at New York, in the county of New York and State of New York, have invented certain new and useful Improvements in Telephone-Transmitters, of which the following is a full, clear, and exact description.

This invention relates to improvements in 10 a telephone transmitting apparatus, in which certain cushioning and other means are provided for the purposes of causing the original voice or sound to be transmitted substantially without distortion and of 15 increasing the current carrying capacity or the resistance variability of the transmitter.

With transmitters now in general use, sound is more or less modified, having extraneous sound vibrations introduced there- 20 with upon the diaphragm or otherwise distorted, especially so when spoken with the mouth close to the transmitter mouth piece. To overcome this defect without drawback in transmission efficiency is the aim of the 25 present invention.

With the above and other objects in view, the invention resides in the peculiar combination and arrangement of parts to be hereinafter more fully described, illus- 30 trated and claimed.

Reference is to be had to the accompanying drawings, forming a part of this specification, in which similar numerals indicate similar parts in all the views, and in which—

35 Figure 1 is a sectional view of a transmitter, embodying the invention, and Fig. 2 is a sectional view of the same on the line 2—2 of Fig. 1, partly broken away.

In the drawings, the numeral 10 designates a diaphragm of somewhat thick carbon (or of any other suitable material, having a carbon electrode or electrodes on its back surface). In parallel with the diaphragm, is placed an electrode supporting 40 plate 11 of suitable insulating material, bearing on the side of the diaphragm semi-circular carbon plates 12, 12, portions of which form electrodes confronting the diaphragm (see Fig. 2). The narrow space 45 between the diaphragm and the carbon plates is occupied and divided into several circular compartments by a soft washer or cushion 13 of felt or like material, as shown in Fig. 2, and the compartments are partly 50 or fully filled with carbon grains or fine 55 carbon balls 14.

The diaphragm 10 is provided with a ring cushion 15 of felt or like, and the electrode supporting plate, with a similar cushion 16 for separating them from the 60 casing 17 within which they are contained. I found that the rigidity of the back electrodes or the electrode plate is not required, but in contrary, the elastic holding serves to eliminate certain ill effect on the dia- 65 phragm, that probably is due to the vibrations of the casing, caused by the vibrations of the bodies and air in contact or connection therewith. The bottom of the casing is made in a form of a movable screw stop- 70 per 18 for the purpose of adjusting the pressure on the cushions. The edges of the diaphragm and the electrode supporting plate may be kept separated from the casing merely by pressing the cushions, care 75 being taken to have them stationed at the center, so that the marginal portions of the cushions will keep them from contact with the casing. These cushions should be ob- 80 served with distinction from damping 80 springs which are employed in some forms of transmitters merely to damp the vibrations of the diaphragms, and from insulat- 85 ing rubber pads or washers which are used to insulate their respective diaphragms from 85 the casings. A diaphragm, if cushioned as herein set forth, acquires the vibratory 90 property, no matter whether it is elastic or not, because of the tendency to return to the initial position, when an external force is 90 applied, moving it away therefrom. With a diaphragm which is fixed or substantially fixed at its peripheral edge, the case is dif- 95 ferent, as the vibratory quality is due to the elasticity of the diaphragm itself, and the 95 vibration is drum-wise.

In the construction shown in the drawings, the carbon contact means or microphones are connected in a parallel-series, however, these may be joined in parallel or 100 in series, when desired.

The casing 17 is attached to a transmitter housing 19 and is provided with a mouth piece 20, the bottom of which is made as large as the space left at the front of the 105 diaphragm, it being desirable to send sound over the whole surface alike as much as possible, instead of concentrating sound at the center thereof. The electrodes 12, 12 are led out by two fine wires to insulated 110 binding posts 21 and 22.

As it is readily seen in the drawings, the

diaphragm 10 and the electrode supporting plate 11 are free from hard contact with the casing 17. The term herein "a hard contact" I mean a contact between the surfaces of two hard bodies, enough to interfere with required movement of one of the bodies. An electrical connection, if it does not noticeably interfere with required movement, is not a hard contact or connection. This structure allows the transmitter diaphragm to respond substantially to the sound entering through the mouth piece without being distorted by the natural vibration of the diaphragm; with this provision the diaphragm is adapted to vibrate simultaneously at the outer portion as well as at its center, or in other words, to vibrate substantially, if not perfectly, bodily under the stresses of the sound transmitting operations, for which the present apparatus is designed. As the diaphragm 10 is adapted to vibrate substantially bodily or it is stiff enough to do so by virtue of the cushions, it is apparent that the effective cross section may be increased, when desired, merely by extending the carbon contact means anywhere desirable along the back of the diaphragm. With the transmitters having diaphragms which vibrate drum-wise, this increase can not be made advantageously beyond certain limit, because of the consequently increasing inertia of heavier electrodes, or of the inactiveness of such diaphragms at their outer portions.

35 The cushion at the back of the electrode supporting plate may be dispensed with, but the clearness would consequently be sacrificed to a certain extent.

By the above described means, I attain 40 my objects to transmit the clear natural voice, and to increase the current carrying capacity of the transmitter.

From the foregoing description, taken in connection with the accompanying drawings, in which I have illustrated the apparatus and arrangement of parts as the best embodiment of my invention, the advantage of construction and arrangement, and the method of operation will be readily 50 apparent to those skilled in the art to which this invention appertains, but I wish it to be understood that the apparatus and arrangement shown herein are merely illustrative, and that such changes may be made, 55 when desired, as to fall within the scope of the invention as claimed.

Having thus described the invention, what I claim as new is:—

1. A telephone transmitter, comprising 60 the combination with a casing; of a diaphragm cushioned by a yielding member against the casing, so as to enable the diaphragm to vibrate bodily in the intended operations, a plurality of carbon contact means disposed along the back of the dia-

phragm, having their effective cross section extended to the outer or edge portion thereof, an electrode holder or supporter bearing electrodes for said carbon contact means, a washer forming compartments for the contact means, and a cushion yieldingly separating the electrode holder or supporter from the casing.

2. A telephone transmitter, comprising a casing, a diaphragm cushioned around the peripheral edge portion thereof by a yielding member against the casing, an electrode supporter, a mouth piece in front of the diaphragm, its bottom being nearly equal in area to the exposed surface of the diaphragm, 75 variable resistance means partitioned by a yielding washer and disposed between the diaphragm and the electrode supporter, in engagement therewith, and a soft cushion supporting the electrode supporter against 80 the casing.

3. A telephone transmitter, comprising the combination with a casing; of a diaphragm, carbon contacts in cooperative relation therewith for transmitting sounds, an electrode holder or supporter bearing electrodes for said carbon contacts, a washer separating the diaphragm and the electrodes, and sealing the carbon contacts, and blankets yieldingly holding under a pressure the diaphragm and the electrode holder or supporter, without making hard contact with the casing, the arrangement thereby 95 allowing bodily vibrations of the diaphragm in the intended operations.

4. A telephone transmitter, comprising a casing, a diaphragm sufficiently stiff to vibrate substantially bodily under the stresses of the intended operations, a plurality of variable resistance means in cooperative relation with the diaphragm, portions of which serve as intermediate electrodes therefor, an electrode plate bearing the electrodes of said variable resistance means, an elastic washer held between the diaphragm and the plate, and means yieldingly holding them under pressure, without hard contact between the diaphragm and the casing.

5. A telephone transmitter, comprising 115 the combination with a casing; of a diaphragm, carbon contact means partitioned by a yielding washer and arranged in engagement with the back surface of the diaphragm at the central and the outer portions of said surface, an electrode holder bearing electrodes for the carbon contact means, and cushions which hold under a pressure the above described members in an operative position, without hard contact between the casing and the other members, said diaphragm thereby being able to vibrate 120 bodily in the intended operations.

6. A telephone transmitter, comprising 130 the combination with a casing; of a dia-

phragm, carbon contact means subdivided by a yielding washer and arranged in engagement with the back surface of the diaphragm at suitable portions of said surface, 5 without concentrating at the center thereof, an electrode holder or supporter secured with the casing and bearing electrodes for said carbon contact means, and cushions yieldingly separating the diaphragm from the casing, the arrangement thereby allowing the diaphragm to vibrate simultaneously at the central and the outer portions thereof in the intended operations.

7. A telephone transmitter, comprising a diaphragm having carbon electrodes there-with or thereon, a plurality of variable resistance means all connected in the same electrical circuit in engagement with said electrodes which are distributed all over the back of the diaphragm, without concentrat-ing at the central portion thereof of the dia-phragm, an electrode supporter bearing the other electrodes for said variable resistance means, and cushions or washers under a pressure sealing said means, and yieldingly holding the above mentioned members within a frame.

8. In a telephone transmitter, a casing or frame, a carbon bearing diaphragm, carbon granules closed by a yielding washer and disposed along the central and outer por-tions of the back of the diaphragm, a holder holding an electrode for said carbon gran-ules, and cushions holding the above de-scribed members under pressure without di-

rect engagement between said members and the casing or frame.

9. A telephone transmitter, comprising the combination with a casing; of a dia-phragm sufficiently rigid to vibrate substan-tially bodily under the stresses of the in-tended operation, carbon contact means dis-posed in engagement with the back of the diaphragm, having the effective cross sec-tion extended to the outer portion of said back of the diaphragm, an electrode holder or supporter resiliently secured with the casing and bearing electrodes for said con-tact means, and cushions yieldingly separat-ing the diaphragm from the casing at the front.

10. In a telephone transmitter, a casing or frame, a carbon bearing diaphragm cush-ioned around the peripheral edge portion thereof by a washer against the casing or frame, carbon granules subdivided by a yielding member and arranged along the back of the diaphragm without concentrat-ing at the central portion of the latter, an electrode bearing plate in engagement with said carbon granules, and an elastic member yieldingly supporting said plate under pres-sure.

In testimony whereof I affix my signature in presence of two witnesses.

NAHO TANAKA.
